UNITED STATES PATENT OFFICE.

GOTTLOB BINDER, OF PHILADELPHIA, PENNSYLVANIA.

IRONING-MACHINE.

SPECIFICATION forming part of Letters Patent No. 568,732, dated October 6, 1896.

Application filed November 18, 1895. Serial No. 569,243. (No model.)

To all whom it may concern:

Be it known that I, GOTTLB BINDER, a citizen of the United States, residing at the city of Philadelphia, in the county of Philadelphia and State of Pennsylvania, have invented 5 certain new and useful Improvements in Ironing-Machines, of which the following is a specification.

My invention has relation to an ironing-machine of the character known as "body-ironers," in which the body of shirts and similar unpolished portions of garments or the like are to be passed between a heated iron and a revolute roller, and in such connection it relates particularly to the construction and arrangement of such a machine.

The principal object of my invention is to provide a simple, durable, effective, and readily-adjustable ironing-machine adapted to 20 permit of the ironing of the body and unpolished portions of a garment or the like.

My invention, stated in general terms, consists of an ironing-machine constructed and arranged in the manner hereinafter described 25 and claimed.

The nature, characteristic features, and scope of my invention will be more fully understood from the following description, taken in connection with the accompanying drawings, forming part hereof, and in which—

Figure 1 is a side elevation of an ironing-machine embodying features of my invention. Fig. 2 is an enlarged cross-sectional view on the line $x-x$ of Fig. 1, illustrating the construction and arrangement of the iron and the garment-roller, and Fig. 3 is a top or plan view of the iron with cover removed to illustrate the construction and arrangement of the air and air and gas pipes.

Referring to the drawings, A and A' represent the end frames of the machine. At the upper end of the frame A is pivoted an arm or lever a , carrying at one end the iron b and connected at its rear end to an extension d of the frame A', around which extension d is coiled a spring d' , resting under the end of the arm a . This arm a is afforded a range of movement on the extension d in up and down directions, but limited as to the extent of the 45 upward movement by a nut d^2 , secured to the upper end of the extension d , as clearly illustrated in Fig. 1 of the drawings.

The iron b consists of a box or chamber b' , the sides and lower end of which are formed by a casting b^2 , while the upper end is closed 55 by a removable and perforated plate or cap b^3 , of the type such as illustrated in Fig. 2.

Within the chamber b' are located pipes b^4 and b^5 , one at each side of the iron, perforated along their under surfaces and connected 60 to gas and air pipes b^6 and b^7 in such a manner that a mixture of the two elements may be fed to and discharged through the perforations in the pipes b^4 and b^5 into the chamber b' and ignited by the application of a match 65 or lighted taper to the perforations in the plate or cover b^3 to heat the lower wall of the stationary ironing - surface, consisting of plates of hardened steel b^8 , applied to the bottom plate of the casting b^2 . A perforated 70 air-pipe b^{10} , extending between the gas and air pipes b^4 and b^5 , feeds fresh air to the jets issuing from said gas and air pipes. The perforations in the top plate or cover b^3 not only permit of the lighting of the gas within 75 the said chamber, but also afford the means for the escape of the products of combustion from the chamber b' during the burning of the gas therein for the heating of the same and for imparting such heat through the 80 plates b^8 to the garment applied to a rotatable iron to be presently more fully described. The smooth steel face plates b^8 , constituting the ironing-surface, are preferably secured to the angular bottom plate b^9 of the casting 85 b^2 by means of screws b^{11} , the heads of which enter countersunk recesses b^{12} , provided in the plates b^8 , substantially in the manner fully illustrated in Fig. 2 of the drawings.

Below the arm a and its iron b is located a 90 roller e , the face of which is of soft material, such as felt or the like, covered with muslin or similar material. (Not shown.) This roller e is connected with a shaft e' , held in the frame A by means of a sliding box e^2 , and to 95 the frame A' by means of a swivel-box e^3 . The shaft e' is secured at the end opposite the roller to a gear-wheel e^4 . Between the roller e and the sliding box e^2 , on the shaft e' , is mounted a collar provided with a rod e^6 , 100 the lower end of this rod being secured to an arm f of a treadle f' in such a manner that when the treadle is depressed the rod e^6 will be raised, thus elevating the roller e toward

the angular steel faces b^8 of the iron b , and at the same time slightly lowering the gear-wheel e^4 . This movement of the shaft e' is accomplished through the swivel and sliding box connections hereinbefore explained.

Below the shaft E' and fixed in the frames A and A' is a bar g , at the left-hand end of which and immediately below the gear e^4 rotates a pinion g' , mounted on a sleeve g^2 , rotating loosely on the bar g and connecting the pinion g' with a gear-wheel g^3 . The gear e^4 meshes with the pinion g' , and when the gear e^4 is slightly elevated by the action of the treadle f' the gear e^4 is still kept in engagement with the pinion g' , the movement of the gear e^4 being but slight. The gear-wheel g^3 meshes with a pinion h , secured on a sleeve h' , rotating upon a stud h^5 , projecting from the frame of the machine and connecting the pinion h with a driving-pulley h^2 . The bar h^3 is longitudinally movable in the frames A and A' of the machine. On the stud h^5 rotates a loose pulley i . The bar h^3 slides through an aperture in stud h^5 , which forms one of the bearings for the bar, which is also supported at the other end in the frame and carries a belt-shifter h^4 . Secured to the bar h^3 is a vertical arm k , the upper end of which is perforated, as at k' , and surrounds and slides upon the bar g as the arm k is shifted. The lower end of the arm k is pivotally secured to one end of a link k^2 , the other end of which is pivoted to another arm f^2 of the treadle f' in such manner that when said treadle is depressed the arm k is shifted to the right, thus actuating the belt-shifter h^4 to the right, in which position a belt l , normally resting on the loose pulley i , is shifted onto the driving-pulley h^2 , thereby rotating, through the sleeve h' and pinion h , the gear g^3 and its pinion g' . Now, as hereinbefore explained, the downward movement of the treadle f' raises the roller e into contact with the heated faces b^8 of the iron, and at the same time, the gear e^4 being meshed with the pinion g' , the shaft e' of the gear e^4 , carrying said roller, begins to rotate.

When the treadle is released, a spring m , coiled around the bar h^3 and bearing, respectively, against the arm k and frame A , serves to shift the bar to the left, thereby actuating the belt-shifter h^4 and causing the belt l to be shifted from the driving-pulley h^2 onto the loose pulley i . As the garment to be ironed is passed over the roller and between it and the stationary iron it will be ironed at the two points p and p' , because the steel faces b^8 of the iron are arranged tangentially to the curved surface of the roller. The steam arises

from contact of the heated iron with the moist garment traveling around the roller e collects in the peaked chamber b^{13} and readily escapes without saturating the surface of the roller e or the garment.

When the garment is wrinkled or seamed, the iron b will move toward or from the garment, the spring d' permitting the adjustment of the iron, and holding its outer end downward in the direction of the roller e and in a plane parallel therewith. Moreover, the spring d' serves to compensate for inequalities of the fabric or different thicknesses of the article being ironed.

Having thus described the nature and objects of my invention, what I claim as new, and desire to secure by Letters Patent, is—

1. In an ironing-machine, a roller, an iron consisting of a box or chamber having a removable, perforated plate or cap, pipes perforated along one of their respective sides located at the sides of the iron and connected to gas and air pipes so that a mixture of the two elements may be fed to and discharged through the perforations into said box or chamber toward the base thereof, said base, comprising two angular plates arranged to form a centrally-peaked chamber above the points of contact of said roller therewith, to permit steam and moisture to collect therein and pass off therefrom without saturating the roller or dampening the garment during the ironing thereof, means for actuating said roller, and a perforated pipe between the gas and air pipes adapted to discharge fresh air toward the perforations of said gas and air pipes, substantially as and for the purposes described.

2. In an ironing-machine, driving and loose pulleys mounted on an apertured stud, a driving-pinion secured to and rotating with said driving-pulley, a movable bar adapted to slide through the aperture of said stud, a belt-shifter carried by said bar, an arm secured to said movable bar, a link and treadle pivotally connected to said arm and adapted to shift the arm, bar and belt shifter in one direction, and a spring coiled around said bar and resting against said arm, said spring adapted to shift said arm, bar and belt-shifter in the opposite direction, substantially as and for the purposes described.

In witness whereof I have hereunto set my signature in the presence of two subscribing witnesses.

GOTTLLOB BINDER.
